ROCK DRILL SUPPORTING AND FEEDING MECHANISM

Jacob E. Feucht, Garfield Heights, Ohio, assignor to Cleveland Rock Drill Division, Westinghouse Air Brake Company, Pittsburgh, Pa., a corporation of Pennsylvania

Application January 14, 1955, Serial No. 481,751

8 Claims. (Cl. 255—45)

This invention relates broadly to rock drills, but more particularly to a support and feed mechanism for rock drills of the percussive type.

One object of this invention is to provide a movable support coupled with a feeding device through which a rock drill, preferably of the drifter type, may be fed to and from the work.

Another object of this invention is to produce such support and feeding mechanism affording possible feed length greater than heretofore possible with supports of equal retracted or minimum length.

Another object of this invention is to produce a rock drill support and feed mechanism of relatively short retracted overall length but capable of long feed, the improved mechanism being characterized by the use of a power feeding element moving at the same rate of speed as that of the rock drill driven thereby, thus resulting in a lower power requirement than needed in mechanisms where the drill moves at a greater rate of speed than its power driven feeding element.

These objects are accomplished by a construction free of complication, and by an arrangement of parts resulting in a compact unit which is strong, durable and efficient.

In the drawings:

Fig. 1 is a side elevational view of a support and feed mechanism embodying the invention. In this view the support is shown fully extended rearwardly with the drill in its rearmost position.

Fig. 2 is a view partly in longitudinal section of the support and feed mechanism shown in Fig. 1. In this view the drill is shown in its foremost position on the upper member of the support.

Fig. 3 is a side elevational view of the mechanism shown in a fully retracted position with the drill in its foremost position on the support.

Fig. 4 is an enlarged cross sectional view taken on line 4—4 in Fig. 3, looking in the direction of the arrows and with the feeding motor omitted.

Fig. 5 is an enlarged cross sectional view taken on line 5—5 in Fig. 3 and looking in the direction of the arrows.

Fig. 6 is an enlarged cross sectional view taken on line 6—6 in Fig. 6.

Fig. 7 is an enlarged cross sectional view taken on line 7—7 in Fig. 1.

Fig. 8 is a side elevational view of a modified construction. In this view the support is fully extended forwardly and the drill is in its foremost position.

Fig. 9 is a view partly in longitudinal section of the support shown in Fig. 8, with the support shown fully retracted and the drill in its foremost position on the support.

Fig. 10 is a side elevational view corresponding to Fig. 9, but with the drill in its rearmost position.

Fig. 11 is an enlarged partial sectional view taken on line 11—11 in Fig. 2.

Referring to the drawings, the drill support may be

2

broadly described as comprising a lower and stationary elongated frame 20 having slidably guided thereon a similar but slidable upper frame 22 on which is also slidably guided a rock drill 24. More particularly, the stationary or supporting frame 20 is formed of a pair of parallel channel bars 25 mounted back to back with a relatively large space between them. The bars 25 are fixed to each other by spacing cross bolts 26 having annular shoulders 27 engaging the inner sides of the channel bars and reduced threaded stems 28 extending through the channel bars to receive nuts 29. Both ends of the channel bars are thus secured together by such cross bolts. Near the front or right ends of the bars as viewed in the drawings, there is fixed to their lower flanges 30 by bolts 31 a depending cone member 32 through which the lower frame 20 may be secured to any supporting device such as a tripod or the like well known in this art. The upper flanges 33 of the channel bars 25 are made special to provide two parallel guideways 34 extending the full length of the bars.

The upper frame 22 is also made of two parallel channel bars 35 with the same space between them as between the channel bars 25, and also secured rigidly to each other by cross bolts 36 each having a sleeve 19 mounted thereon with its ends abutting the inner walls of the channel bars 35 while the head and nut of the bolt hold the bars tightly against the ends of the sleeve. Frame 22 is somewhat shorter than frame 20 and has the lower flanges 37 of its channel bars forming guides fitted within the guideways 34 for slidable guide movement of the upper frame longitudinally on the lower frame. The upper flanges 38 of the bars 35 form parallel guides having fitted over them guideways 39 provided within a saddle 40, thereby enabling slidable guided movement of the saddle longitudinally on the upper side of upper frame 22. To the saddle 40 is fixed by bolts 41 and changing plates 42 the rock drill 24, here shown to be of the drifter type. This rock drill is of the usual type well known in this art, and may briefly be described as including a cylinder 43 closed at one end by a back head 44 and at the other by a chuck housing 45. Within the cylinder is reciprocable a piston, not shown, adapted to deliver impacts in rapid succession on a drill steel 46 which extends forwardly from chuck housing 45.

From the foregoing description, it will be understood that the drill support comprises an elongated stationary supporting frame 20 in the upper side of which is slidably guided for longitudinal movement thereon an upper elongated frame 22. On the upper side of frame 22 is slidably guided, for longitudinal motion thereon, the rock drill 24.

Referring now to the feeding mechanism, that is the power actuated mechanism susceptible of imparting slidable movement to the upper frame and the drill relative to the lower frame. Preferably this mechanism includes a pressure fluid actuated reversible rotary motor 50 of any suitable type, well known in this art, having pressure fluid admitted thereto through a conduit such as 48 and controlled by any suitable throttle valve, not shown. The motor housing is made with an integral bracket 49 extending laterally therefrom, through which the motor is fixed to one side near one end of the supporting frame 20. More particularly, as shown in Fig. 6, bracket 49 is fixed by bolts 47 to the lower flange 30 of one of the channel bars 25, with the motor located alongside of the frame 20 and adjacent one end thereof. Motor 50 has a motor shaft 51 extending therefrom through a hole 52 provided through the side wall of the channel bar 25 to which the motor is attached, while the other bar is provided with a similar hole 53. Between the two channel bars, 25, the motor shaft 51 is reduced to form an annular

shoulder 54 against which abuts one side of a sprocket wheel 55 keyed on the reduced end of the shaft for rotation therewith and held axially thereon by a washer 56 and bolt 57 which extends through hole 53. Sprocket wheel 55 is in mesh with a chain 60 having both ends fixed to the underside of the saddle 40 by a clamping plate 61 and belts 62 (see Fig. 2). With the understanding that the right and left ends of the drill support as viewed in Figs. 1 to 3, are hereinafter referred to as its front and rear ends respectively, and with particular reference to Fig. 2, from the drill 24 chain 60 extends rearwardly over a sprocket wheel 63 operatively mounted on frame 22 adjacent the rear end thereof between the channel bars 35. From sprocket wheel 63, chain 60 extends forwardly over a roller 64 operatively mounted on frame 22 adjacent the front end thereof. As shown in Fig. 4, roller 64 is rotatably mounted on the sleeve on spacer 19 fitted on the bolt 36 and clamped between the inner walls of the channel bars 35 by the head of the bolt and its nut. This construction gives rigidity to the upper frame while providing an adequate shaft on which roller 64 is free to rotate. From roller 64, chain 60 extends rearwardly and downwardly over the motor sprocket 55 and into the lower frame 20, from where it extends forwardly over a roller 65 operatively mounted within the front end of the frame 20. This last roller is a replica of roller 64 and is mounted in the same manner. From front roller 65, chain 60 extends rearwardly and upwardly into upper frame 22 over a third roller 66 mounted within the upper frame 22 adjacent rollers 64 and the front end of the frame. From this last roller the chain again extends forwardly over a sprocket wheel 67 mounted within the front end of upper frame 22, from where it extends again rearwardly to the rock drill 24 where it is fastened. For the sake of better identification, the rollers 64 and 66 may be referred to as adjacent idlers or intermediate wheels mounted within the front end portion of upper frame 22, while the sprockets 67 and 63 may be called end wheels mounted on the upper frame and the sprockets 65 and 55 end wheels mounted on the lower frame, with the sprocket 55 also referred to as the motor sprocket or wheel.

In order to limit travel of the rock drill on the upper frame 22, the upper frame is provided with the cross belts 70 located immediately below the upper flanges 38 as clearly shown in Fig. 7, each having its head and nut engaging especially shaped short sleeves 71 nested under the flanges 38 and abutting against the side walls of the channel bars 35. These bolts are located within the path of the saddle 40 and are therefore adapted to be engaged thereby to limit movement of the drill on frame 22. One bolt is located near the rear end of the frame while the other is located adjacent the front end thereof.

To also limit slidable movement of the upper frame 22 on the lower one 20, on the inside wall of each of the channel bars 35 of the upper frame 22, is fixed by screws a flat plate or stop 68 (Fig. 2) depending into the lower frame 20 and engageable with stop screws 69 screwed into the channel bars 25 and protruding interiorly thereof. Two stop screws 69 are carried by each side of frame 20, one located near the rear end thereof and the other within its forward portion.

Also mounted on the front end of the upper frame 22, is a drill steel centralizer 72 of any suitable type, many of which are well known in this art. Briefly it generally includes two arms, one which is shown in the drawings, each slideably and pivotably mounted on opposite sides of the frame on a shaft 73 fixed thereon by end fasteners 74. The two arms of the centralizer are generally biased by a spring 75 into locked operative position to provide a guiding bearing for the drill steel 46. When desired the arms can be unlocked by axial movement on shafts 73 against springs 75. Another similar centralizer 76 is operatively mounted on the front end of the stationary frame 20. This last centralizer is taller than the other one

with its drill steel bearing coaxially with that of centralizer 72.

Except for the centralizers 72 and 76, the modified construction shown in Figs. 8 to 10 include all the same parts as the construction above referred to. The main difference between the two constructions resides in the location of the idlers 164 and 166, which in this construction is still adjacent to each other but located within the rear end portion of the upper frame 122. With this change in the location of the idlers, the assembly is movable from the fully retracted position shown in Fig. 10 with the drill 124 in a rearmost position on the upper frame 122 to the full forward extension shown in Fig. 8 with the drill in a foremost position on the upper frame. In the construction shown in Figs. 1 to 3, the assembly is movable from the full rearward extension shown in Fig. 1 with the drill in a rearmost position on the upper frame 22, to the fully retracted position shown in Fig. 3 with the drill in a foremost position on the upper frame.

In the operation of the mechanism shown in Figs. 1 to 7, assuming the drill 24 to be in its rearmost position as shown in Fig. 1, it can be operated to deliver impact and rotation in the usual manner to the relatively long drill steel 46 for starting the hole intended to be drilled. In this instance, the drill steel is well supported or guided by the two drill steel centralizers 72 and 76 which maintain the drill steel in axial alignment with the rock drill 24. Concurrently with the start of the rock drill, motor 50 may also be started to impart rotation to motor sprocket 55 in a clockwise direction in Fig. 2.

An important feature of this invention is to provide means whereby the relative short sliding bearings between the lower and upper frame when fully extended rearwardly, will gradually become longer and therefore become more efficient immediately after the start of the drill hole. This feature is accomplished by virtue of differential resistance to travel of sections of chain 60. It will be noted that the section of the chain extending from the motor sprocket 55 over roller 65 to roller 66, which is hereinafter referred to as first section, having only one sharp turn over roller 65, has less resistance to travel than when combined with the second section which extends from roller 66, over sprocket 67 to rock drill 24. As the first section is put under tension by rotation of the motor sprocket 55, roller 66 together with the second section of the chain will remain stationary relative to the upper frame 22 and move therewith relative to the lower frame while the first section of the chain moves over roller 65. Thus it will be understood that original feeding motion is imparted to the drill steel 46 by sliding movement of the upper frame 22 on the lower frame 20, while the drill 24 remains stationary on the upper frame. This condition remains until the upper frame stops 68 engage the front stop member 69, which limits further forward movement of the upper frame relative to the lower one. Thereafter the entire driven section of the chain, that is the first section combined with the second one, will move for imparting forward feeding motion to the rock drill 24 until its saddle 40 contacts the forward stop 71.

It will also be noted that by virtue of the disposition of the chain as above described, for a given rotary speed of motor 50, the drill moves at a uniform rate of speed when fed with or independently of the upper frame 60. Since no speed multiplying mechanism is incorporated in this structure, it can operate effectively for feeding the drill steel to and from work with a minimum power requirement.

As shown in Fig. 3, the two centralizers 72 and 76 are located so that when the drill 24 reaches the end of its forward feeding travel, it remains short of the centralizers, which therefore need not be removed or swung open to allow complete forward movement of the rock drill.

When it is desired to remove the drill steel 46 from the drilled hole, that is feed the rock drill rearwardly,

motor 50 is caused to rotate in the opposite direction. In this instance the first driven section of chain 60, from motor sprocket 55 to sprocket 63, having only one sharp turn over roller 64, has less resistance to travel than when combined with the second section from sprocket 63 to rock drill 25. As this first driven section is put under tension by rotation of the motor sprocket 55, sprocket 63 together with the second section of the chain will remain stationary relative to the upper frame 22 and move therewith relative to the lower frame while the first section of the chain moves over roller 64. This condition will remain until the upper frame stops 68 engage the rear stop member 69, which limits further rearward movement of the upper frame relative to the lower one and the chain and motor assume the position shown in Fig. 2. Thereafter the entire driven section of the chain, that is the first and second ones will move for imparting rearward feeding motion to the rock drill 24 until its saddle 40 contacts the rear stop 71.

From the foregoing description, it will be understood that during forward feeding motion, only the portion of the chain from motor sprocket 55 to rock drill 24 passing over rollers 65, 66 and sprocket 67 is effective, and can therefore be referred to as the chain driven front portion, while the other portion of the chain is nothing more than a trailing position. Similarly when feeding rearwardly, the chain driven rear portion extends from motor sprocket 69 over roller 64 and sprocket 63 to the rock drill, while the other portion is nothing more than a trailing portion.

Since the operation of the modified construction shown in Figs. 8 to 10 is substantially the same as the one above referred to, no detailed description of it is thought necessary. Because the rollers 164 and 166 are located adjacent the rear end of the upper frame 122, upon rotation of motor 50 in a clockwise direction, the upper frame 122 with the drill located on the rear end thereof is first moved forwardly, and after it has reached its front stop, not shown, corresponding to 69 in Fig. 2, the drill 124 will move forwardly relative to the upper frame until it reaches its front stop 171.

Upon rotation of the motor 50 in the other direction, the upper frame 122 from its forward extended position will first be moved backward with the drill 124 stationary on its front end until the upper frame engages its rear stop, not shown, and assumes the position shown in Fig. 9. Thereafter the rock drill 124 will move rearwardly until its saddle contacts the rear stop 171.

In this modified construction, because the upper frame 152 is made to extend forward of the lower frame 120, and the rock drill 124 forward of the upper frame, it is not possible to equip this support with centralizers equivalent to 72 and 76.

The details of structure and arrangement of parts shown and described may be variously changed and modified without departing from the spirit and scope of the invention.

I claim:

1. A rock drill supporting and feeding mechanism comprising an elongated stationary lower frame, an upper frame slidably guided longitudinally on the lower frame, a rock drill slidably guided longitudinally on the upper frame, said mechanism being retractable into a position of said upper frame within the length of the lower frame and the rock drill near one end of the upper frame, and extensible into a position of the major portion of the upper frame beyond one end of the lower frame with the rock drill near the other end of the upper frame, means for effecting said retraction and extension including a power driven sprocket wheel mounted within one end of said lower frame, an endless chain in mesh with said sprocket wheel and fixed to said rock drill, end wheels having said chain passing over them operatively mounted one within the other end of said lower frame and one within each end of said upper frame, and adj-

cent idlers operatively carried by said upper frame near one end thereof being engaged and passed over by portions of said chain, one idler by the portion of the chain between the wheels carried by the rear ends of said frames and the other idler by the portion of the chain between the wheels carried by the front ends of said frames.

2. A rock drill supporting and feeding mechanism comprising an elongated stationary lower frame, an upper frame slidably guided longitudinally on the lower frame, a rock drill slidably guided longitudinally on the upper frame, said mechanism being retractable into a position of said upper frame within the length of the lower frame and the rock drill near one end of the upper frame and extensible into a position of the major portion of the upper frame beyond one end of the lower frame with the rock drill near the other end of the upper frame, means for effecting said retraction and extension including a power driven sprocket wheel mounted within one end of said lower frame, an endless chain in mesh with said sprocket wheel and fixed to said rock drill, said chain extending rearwardly from the rock drill over an end wheel mounted within the rear end of the upper frame, then forwardly over a first intermediate wheel carried by said upper frame near one end thereof, then rearwardly and downwardly over said sprocket wheel, then forwardly over one end wheel mounted within the front end of said lower frame, then rearwardly and upwardly over a second intermediate wheel carried by said upper frame adjacent the first intermediate wheel, then forwardly over one end wheel carried within the front end of the upper frame, then rearwardly to said rock drill.

3. A rock drill supporting and feeding mechanism comprising an elongated stationary lower frame, an upper frame slidably guided longitudinally on the lower frame, a rock drill slidably guided longitudinally on the upper frame, said mechanism being retractable into a position of said upper frame within the length of the lower frame and the rock drill near one end of the upper frame and extensible into a position of the major portion of the upper frame beyond one end of the lower frame with the rock drill near the other end of the upper frame, means for effecting said retraction and extension including a power driven sprocket wheel mounted within one end of said lower frame, an endless chain in mesh with said sprocket wheel and fixed to said rock drill, and directional wheels operatively carried by said frames each engaged by said chain for changing its direction longitudinally of said frames, said wheels including one within the other end of said lower frame, one within each end of said upper frame, and two more carried by said upper frame between the end wheels thereof.

4. A rock drill supporting and feeding mechanism comprising an elongated stationary lower frame, an upper frame slidably guided longitudinally on the lower frame, a rock drill slidably guided longitudinally on the upper frame, said mechanism being extensible into a position with more than one half the length of the upper frame extending rearwardly beyond the rear end of the lower frame and with the rock drill near the rear end of the upper frame, and retractable into a position of said upper frame within the length of the lower frame with the rock drill near the front end of the upper frame, means effecting extension and retraction of said mechanism including a power driven sprocket wheel operatively mounted within one end of said lower frame, an endless chain in mesh with said sprocket wheel and fixed to said rock drill, and wheels having said chain passing over them operatively mounted one within the other end of said lower frame and one within each end of said upper frame, and front and rear adjacent idlers operatively carried by said upper frame near the front end thereof being engaged and passed over by portions of said chain extending respectively between the wheels carried by the front and rear ends of said frames.

5. A rock drill supporting and feeding mechanism

comprising an elongated stationary lower frame; an upper frame slidably guided longitudinally on the lower frame; a rock drill slidably guided longitudinally on the upper frame, said mechanism being extensible into a position with more than one half the length of the upper frame extending rearwardly beyond the rear end of the lower frame and with the rock drill near the rear end of the upper frame, and retractable into a position of said upper frame within the length of the lower frame with the rock drill near the front end of the upper frame, means 10 effecting extension and retraction of said mechanism including a reversible rotary motor fixed to the lower frame, a sprocket wheel operatively mounted within one end of the lower frame driven by said motor, and a chain in mesh with said sprocket wheel and fixed to said rock drill, said chain extending rearwardly from the rock drill over an end wheel operatively mounted within the rear end of the upper frame, then forwardly over a first intermediate wheel carried by said upper frame near the front end thereof, then rearwardly and 20 downwardly over said sprocket wheel, then forwardly over an end wheel mounted within the other end of said lower frame, then rearwardly and upwardly over a second intermediate wheel carried by said upper frame adjacent the first intermediate wheel, then forwardly over an end wheel carried within the front end of the upper frame, then rearwardly to said rock drill.

6. A rock drill supporting and feeding mechanism comprising an elongated stationary lower frame, an upper frame slidably guided longitudinally on said lower frame, a rock drill slidably guided longitudinally on the upper frame, a drill steel extending longitudinally from said rock drill, a drill steel retainer mounted on said frame near the front ends thereof coaxially aligned with the center axis of said rock drill and adapted to guide and support said drill steel, said mechanism being extensible into a position with more than one half the length of said upper frame extending rearwardly beyond the rear end of said lower frame and with said rock drill near the rear end of said upper frame, and retractable into a position of said upper frame within the length of said lower frame with the front end of the upper frame short of the centralizer of the lower frame and with the rock drill near the front end of but short of the centralizer carried by said upper frame, means for effecting extension and retraction of said mechanism including a reversible rotary motor carried by said lower frame, a sprocket wheel operatively mounted within one end of said lower frame driven by said motor, an endless chain in mesh with said sprocket wheel and fixed to said rock drill, and directional wheels 50 operatively carried by said frames each engaged by said chain for changing its direction longitudinally of said frames, said wheels including one within the other end of said lower frame, one within each end of said upper frame, and two more carried by said upper frame near the front end thereof between its two end wheels.

7. A rock drill supporting and feeding mechanism comprising an elongated stationary lower frame, an upper

frame slidably guided longitudinally on the lower frame, a rock drill slidably guided longitudinally on the upper frame, said mechanism being extensible into a position of more than one half the length of the upper frame extending forwardly beyond the front of the lower frame and with the rock drill near the front end of the upper frame, and retractable into a position of said upper frame within the length of the lower frame with the rock drill near the rear end of the upper frame, means effecting extension and retraction of said mechanism including a power driven sprocket wheel operatively mounted within one end of said lower frame, an endless chain in mesh with said sprocket wheel and driven thereby fixed to said rock drill, and wheels having said chain passing over them operatively mounted one within the other end of said lower frame and one within each end of said upper frame, and front and rear adjacent idlers operatively carried by said upper frame near the rear end thereof being engaged and passed over by portions of said chain extending respectively between the wheels carried by the front and rear ends of said frames.

8. A rock drill supporting and feeding mechanism comprising an elongated stationary lower frame, an upper frame slidably guided longitudinally on the lower frame, a rock drill slidably guided longitudinally on the upper frame, said mechanism being extensible into a position of more than one half the length of the upper frame extending forwardly beyond the front of the lower frame and with the rock drill near the front end of the upper frame, and retractable into a position of said upper frame within the length of the lower frame with the rock drill near the rear end of the upper frame, means effecting extension and retraction of said mechanism including a reversible rotary motor fixed to the lower frame, a sprocket wheel operatively mounted within one end of the lower frame driven by said motor, and a chain in mesh with said sprocket wheel and driven thereby fixed to said rock drill, said chain extending rearwardly from the rock drill over an end wheel operatively mounted within the rear end of said upper frame, then forwardly over a first intermediate wheel carried by said upper frame over the rear end thereof, then rearwardly and downwardly over said sprocket wheel, then forwardly over an end wheel mounted within the other end of said lower frame, then rearwardly and upwardly over a second intermediate wheel carried by said upper frame adjacent the first intermediate wheel, then forwardly over an end wheel carried within the front end of said upper frame, then rearwardly to said rock drill.
